UNITED STATES PATENT OFFICE

MICHAEL HALLWARD, OF PASADENA, CALIFORNIA

DESIGN FOR A CHILD'S TOY CHEST

Application filed October 10, 1932. Serial No. 45,267. Term of patent 7 years.

To all whom it may concern:

Be it known that I, MICHAEL HALLWARD, a subject of the King of Great Britain, residing at Pasadena, in the county of Los Angeles and State of California, have invented a new, original, and ornamental Design for a Child's Toy Chest, of which the following is a specification, reference being had to the accompanying drawing, forming a part thereof.

The figure shown in the accompanying drawing is a perspective view of the child's toy chest of this design.

I claim:

The ornamental design for a child's toy chest, as shown.

MICHAEL HALLWARD.
